UNITED STATES PATENT OFFICE.

THOMAS SULLIVAN, OF BELLEVILLE, CANADA.

REVERSING-VALVE FOR STEAM-ENGINES.

SPECIFICATION forming part of Letters Patent No. 761,426, dated May 31, 1904.

Application filed October 14, 1903. Serial No. 177,081. (No model.)

To all whom it may concern:

Be it known that I, THOMAS SULLIVAN, a citizen of Canada, and a resident of the city of Belleville, in the county of Hastings and Province of Ontario, Canada, have invented new and useful Improvements in Reversing-Valves for Steam-Engines, of which the following is a specification.

The object of my improvement is to establish a more perfect reverser for a steam-engine than the present reverser in use, and my invention will have a tendency to do away with the friction of link-motion and the complication of other steam-reversers, such as Christopher's patent, No. 474,212, dated May 12, 1892, and Gilmore's patent, No. 632,459, dated September 5, 1899, and my invention is a simplification of those reversers. I do not limit my reverser to any special steam-chest valve, and by making minor improvements to slide or rocking valves my reverser can be applied to any of them.

My present invention is illustrated in the accompanying drawing, in which the figure 25 shows the construction, combination, and arrangement of valves and connecting-pipes herein described, and pointed out in the claim hereto appended.

On the drawing, A is the throttle as well as 30 a reversing valve.

B is the exhaust as well as a reversing valve.

A and B are simply three-way stop-cock shells with two-way valves in them.

C and D represent the reversing-levers and 35 are connected to the two-way valves. With

the position of levers C and D as is represented on the drawing the engine would be going ahead. Remove levers C and D to the center and it would close the valves and stop the motion. Remove levers C and D to pipe 40 F and it reverses the engine.

When the engine is making sixty revolutions and upward it reverses as if there is no dead-center by quickly moving levers C and D to reversing position.

The steam can be checked down by moving lever C toward the center. Steam enters valve A on the opposite side of the valve as it appears on the drawing and passes down pipe E to the engine and is discharged through 50 pipe F and out through exhaust-valve B, and when reversed the steam-passage is reversed.

What I claim as my invention is—

In a reversing-valve device, a supply-pipe 55 and an exhaust-pipe, valve connections between said pipes, a two-way valve in each of said connections, and valve-levers for said valves in proximity to each other, whereby the valves may be worked by hand together or 60 independently of each, substantially as described.

In testimony whereof I have signed my name to this specification in the presence of two subscribing witnesses.

THOMAS SULLIVAN.
